COLLAPSIBLE CARTON

Frederick A. Sunderhauf, Rutherford, N. J., and Frank W. Broderick, New Brighton, N. Y., assignors to Reynolds Metals Company, Richmond, Va., a corporation of Delaware

Application October 6, 1939, Serial No. 298,170

4 Claims. (Cl. 206—44)

This invention relates to a new collapsible carton adapted to be manufactured economically by die-stamping operations, to be shipped flat by the box manufacturer to the food packer or other user of the carton, and further adapted for easy assembly into a strong, stable, attractive carton which is rigid enough to adequately protect articles packed therein.

Cartons embodying our invention are particularly satisfactory when made from cardboard covered with metal foil, particularly aluminum foil.

Heretofore, a variety of cartons have been suggested but none has combined all of the characteristics embodied in our invention, namely, economy and simplicity of manufacture, flat packing, ease of assembly, strength and rigidity when assembled.

Therefore, it is an object of our invention to produce from the single blank, formed by die-cut and die-scoring operations, a flat collapsible carton which may be later assembled in a strong, rigid and attractive assembly.

It is a further object of our invention to produce a carton, the sides and top of which will be formed from a single piece and which, when assembled, are of a rounded configuration, the said rounded top member being held in shape by the end members of the carton.

It is a further object of our invention to produce a carton, from a simple one piece die-cut and die-scored blank, economically, with hinged dividing panels for the interior of the carton formed from material obtained centrally of the blank, with the elements of the carton so arranged that it is possible to inspect the merchandise within the carton.

With these and other objects in view, our invention consists in the construction and novel combination and arrangement of parts, herein-after fully described, and illustrated in the accompanying drawings in reference to present embodiments thereof, it being understood that various changes in the form, proportion and minor details in the construction, within the scope of the claims, may be resorted to without departing from the spirit or sacrificing any of the advantages of the invention.

In the drawings, Fig. 1 illustrates a plan view of a one piece die-cut, die-scored blank suitable for the production of a carton embodying one form of our invention;

Fig. 2 is a perspective view of the carton, partially assembled, formed from the blank shown in Fig. 1;

Fig. 3 is similar to Fig. 2, with one side of the carton assembled;

Fig. 4 is similar to Fig. 2, but illustrating a carton fully assembled;

Fig. 5 illustrates a stack of cartons similar to the carton illustrated in Fig. 4, but said cartons being collapsed flat for shipping;

Fig. 6 is a plan view of a one piece die-cut, die-scored blank adapted to produce a carton embodying an alternate form of our invention;

Fig. 7 is a perspective of the blank illustrated in Fig. 6, partially folded, but collapsed flat for shipping purposes and adapted for easy assembly later;

Fig. 8 is a perspective of a carton partially assembled, formed from the blank illustrated in Fig. 6;

Fig. 9 is a perspective of the carton illustrated in Fig. 8 except that the same is fully assembled;

Fig. 10 is a cross section taken along the line 10—10 of Fig. 9, and

Fig. 11 is a cross section of the carton's stock illustrating a layer of cardboard surfaced on both sides with layers of aluminum foil.

25 Referring to Figs. 1—5, a carton 10, embodying one form of our invention, is formed from a one piece integral blank 12, by die-cutting and die-scoring operations, and comprises a bottom panel member 14, a top panel member 16, adapted to be shipped flat and further adapted to be curved to form a one piece top and sides (see Fig. 4) for the carton 10, bottom overlapping panel members 18 which are provided with locking tabs 20 adapted to cooperate with locking slots 22, carton end members 24, bottom bridging and spacing members 26, top bridging and spacing members 28 and glue flap 30.

It will be observed that glue flap 30 is fastened to the free inner edge of bottom member 14, by means of an appropriate adhesive, and that when so fastened thereto the unique construction of the box permits its flat collapse, as indicated in Fig. 5, with curved top member 16 lying flat and with both end members lying flat, one folded inwardly and upwardly and the other folded downwardly and outwardly, this being because of the parallel link formation of the members. It will be observed that bottom member 14 is hingedly and swingably connected to bottom bridging and spacing members 26 which will likewise connect to end members 24, which latter are likewise connected to top bridging and spacing member 28, which in turn will connect to the 50 ends of top portion 16; this being possibly be-

cause of the separating score lines, indicated generally as at 32.

It will also be observed that the top bridging and spacing members 28 are shorter than the bottom bridging and spacing members 26 and lie within a relatively flattened portion of the curved top member 16, when the carton is assembled.

When assembling the box, the bridge members will turn inwardly, and the overlapping bottom members 18 are tensioned inwardly flatwise and locked in position in bottom member 14, thereby placing top member under tension and forcing it to conform to the shape of end members 24, and also fixing the bridging and spacing members 26 and 28 in place so that they automatically space the end members 24 inwardly from the outer ends of the carton, indicated as at 34. This gives a strong and stable construction, as the members 26 and 28 are folded inwardly over their respective top and bottom members, giving a double thickness at such points of fold, thus giving rigidity to the carton. An opening 36 may be provided in top member 16, which opening may be attractively provided with a bridge member 38, if desired. This permits an inspection of the goods within the carton 10, if desired, and where such an opening is utilized, the entire carton may be placed in Cellophane or some other transparent wrapping medium.

Referring to Figs. 6-10, instead of having the form of opening illustrated in Figs. 1-4, we may provide top member 16 with two hinged panel portions 40, hinged to a longitudinally running strip member 42, the two hinged panel portions 40 being adapted to be folded downwardly in the carton, as best shown in Figs. 9 and 10, thereby affording dividing panels for the carton.

In Fig. 11 there is illustrated a layer of cardboard 43 lined on each side with aluminum metal foil as at 44.

It is obvious that variations may be practised in respect to our invention above described, and therefore reference should be had to the appended claims which define the scope of our invention.

Having described our invention, what is now claimed is:

1. A flat, collapsible carton produced by a one-piece die-cut and die-scored blank, which includes a bottom member, a one-piece top member forming the top and sides of the carton, end members positioned inside of the outer limits of the said top and bottom members, bridging and stiffening panels connecting the top and bottom members to the end members, locking means to

lock the carton in assembled position, and further panels hinged to said top member and adapted to be folded downwardly and inwardly into engagement with said bottom member to strengthen said carton against outside pressure when in assembled condition.

2. A flat, collapsible carton produced by a one-piece die-cut and die-scored blank, which includes a bottom member, a one-piece top member forming the top and sides of the carton, end members positioned inside of the outer limits of the said top and bottom members, bridging and stiffening panels connecting the top and bottom members to the end members, locking means to lock the carton in assembled position and a further panel hinged to said top member and extending longitudinally of said carton, said panel being adapted to be folded downwardly and inwardly into engagement with said bottom member to strengthen said carton against outside pressure when in assembled condition.

3. A flat, collapsible carton produced by a one-piece die-cut and die-scored blank, which includes a bottom member, a one-piece top member forming the top and sides of the carton, end members positioned inside of the outer limits of the said top and bottom members, bridging and stiffening panels connecting the top and bottom members, to the end members, locking means to lock the carton in assembled position, and further panels hinged to said top member and adapted to be folded downwardly and inwardly into engagement with said bottom member to strengthen said carton against outside pressure when in assembled condition, said panels separating said carton into a plurality of compartments extending longitudinally thereof.

4. A flat, collapsible carton produced by a one-piece die-cut and die-scored blank, which includes a bottom member, a one-piece top member forming the top and sides of the carton, end members positioned inside of the outer limits of the said top and bottom members, bridging and stiffening panels connecting the top and bottom members to the end members, locking means to lock the carton in assembled position, and further panels hinged to said top member and adapted to be folded downwardly and inwardly into engagement with said bottom member to strengthen said carton against outside pressure when in assembled condition, said panels also bearing against said end members and limiting inward movement thereof.

FREDERICK A. SUNDERHAUF.
